UNITED STATES PATENT OFFICE.

JOHN SPOLJAR, OF DETROIT, MICHIGAN.

WINDOW-SASH.

1,316,065.

Specification of Letters Patent. Patented Sept. 16, 1919.

Application filed December 9, 1918. Serial No. 265,833.

To all whom it may concern:

Be it known that I, JOHN SPOLJAR, a subject of the King of Hungary, residing at Detroit, in the county of Wayne and State of Michigan, have invented certain new and useful Improvements in Window-Sashes, of which the following is a specification, reference being had therein to the accompanying drawings.

10 This invention relates to window sashes, and the primary object of my invention is to furnish a window frame with hingedly connected window sashes and retaining devices which will permit of either of the sashes 15 being swung to an open position for cleaning or ventilating purposes, or all of the sashes removed for repair or cleaning purposes. Such sashes permit of the window panes and sash rails being cleaned without 20 danger of a person falling out of the window and since one or more of the sashes can be opened, a desired degree of ventilation can be obtained for a compartment having window sashes in accordance with my invention.

25 Another object of my invention is to furnish a window frame with removable sashes and novel retaining members for holding the sashes normally in the window frame. The retaining members can be easily and quickly 30 adjusted so as to safely hold the plurality of sashes within the frame.

A further object of my invention is to provide a window frame and detachable sashes therefor, the latter consisting of parts that 35 are inexpensive to manufacture, durable and highly efficient for the purposes above specified.

The above and other objects are attained by a mechanical construction which will be 40 hereinafter specifically described and then claimed, and reference will now be had to the drawings, wherein

Figure 1 is a front elevation of a window frame provided with a plurality of sashes in 45 accordance with my invention;

Fig. 2 is a vertical sectional view of the window frame showing the lower sash in an open position in full lines, the upper sash swung to an open position in dotted lines, and a fly screen in position to exclude insects 50 from a compartment furnished with the window frame and sashes;

Fig. 3 is a horizontal sectional view taken on the line III—III of Fig. 2, looking in the 55 direction of the arrows; and

Fig. 4 is a perspective view of a portion

of the window frame showing retaining members.

In the drawings, the reference numeral 1 denotes a window frame provided with stiles 2, and a retaining strip or bead 3, said retaining strip or bead being at the outer edges of the stiles 2 so as to provide an abutment for sashes 4, 5 and 6, the sashes 4 and 5 being practically the same area and the sash 6 65 smaller than the sashes 4 and 5 and disposed in the upper end of the window frame 1. The sashes 4, 5 and 6 are hingedly connected together, as at 7, thus permitting of the lower sash 4 being swung upwardly into 70 parallelism with the intermediate sash 5 or the upper sash 6 swung downwardly relative to the intermediate sash 5. It is also possible to swing the sashes 5 and 6 inwardly when the lower sash 4 is held, or as will hereinafter 75 appear, to completely remove all of the sashes.

The lower rail 8 of the lower sash 4 has a conventional form of latch 9 adapted to engage in a keeper plate 10 centrally of the sill 11 of the window frame 1, and the top or meeting rail 12 of said lower sash has its ends recessed, as at 13, so as to receive studs 14, carried by the stiles 2 of the window frame. The studs 14 do not interfere with 85 the opening of the lower sash 4, and said studs engage in similar recesses in the ends of the lower rail 15 of the intermediate sash 5, said studs assisting in supporting the intermediate sash 5, particularly when the 90 lower sash 4 is in an open position.

The top rail 16 of the upper sash 6 has a yoke shaped keeper 17 adapted to receive the crank end 18 of a turn bolt 19 set in a recess 20 in the lintel 21 of the window frame 1. 95 The turn-bolt 19 is retained within the lintel recess 20 by a plate 22, as best shown in Figs. 2 and 3, said turn bolt and the keeper constituting means for holding the upper sash 6 in a closed position, but permitting of 100 said upper sash being swung outwardly for ventilating purposes.

The stiles 2 are recessed and cut away as at 23, to provide clearance for turn bolts 24 held in bearings 25 at the inner edges of 105 the window frame, said turn-bolts having crank ends 26 to engage the side rails of the intermediate sash 5 and hold said sash in a closed position.

On the edges of the stiles 2 are pivoted 110 clips 27 and 28, the former being swung inwardly to hold the lower sash 4 in a raised

open position parallel with the intermediate sash 5 as shown in Fig. 2, and the latter may be swung inwardly, after the lower sash 4 is opened, to hold said sash at an angle relative to the window frame, for ventilating purposes.

The sill 11 of the window frame has a box structure containing a roller 30 for a wire screen 31, and said screen is adapted 10 to extend through a slot 32 in the sill 11 and have its upper end supported by hooks 33 on the stiles 2. The screen is raised into position when the lower sash 4 is opened, and said screen will prevent flies and other 15 insects from entering a compartment provided with a window frame and sashes in accordance with my invention.

From the foregoing it will be observed that all of the window sashes can be readily 20 removed from the window frame when it is desired to clean the window panes or repair said sashes, consequently lives are not in danger by leaning on to the window frame in order to clean the outside of the sashes. 25 With the sashes fitting against the frame strips or beads and so held by turn bolts or retaining members, it is practically impossible for the elements or foreign matter to pass through the window frame, and the 30 manner in which the sashes are locked in a closed position renders the window burglar proof. With the frame and sashes constructed of sheet metal and wire glass the entire structure is fire proof, but sashes 35 made of wood and in accordance with my

invention can be installed in ordinary window frames by simply equipping said frames with the retaining members.

Furthermore the manner of locking the sashes precludes rattling, yet permitting of any desired degree of ventilation at the top or bottom of the window frame.

It is thought that the utility of my invention will be apparent without further description, and while in the drawing there is 45 illustrated a preferred embodiment of my invention, it is to be understood that the structural elements are susceptible to such variations and modifications as fall within the scope of the appended claim. 50

What I claim is:—

The combination with a window frame, and stiles therein, of lower, intermediate and upper window sashes hingedly connected together and adapted to be bodily removed 55 from said window frame, studs carried by said stiles between the lower and intermediate sashes, a turn bolt carried by said window frame adapted to retain the upper sash in a closed position, and a latch carried by 60 the lower sash adapted to engage in said window frame and retain the lower sash in a closed position.

In testimony whereof I affix my signature in the presence of two witnesses.

JOHN SPOLJAR.

Witnesses:

ANNA M. DORR,
CHAS. W. STAUFFIGER.
